(57) **CLAIM**

The ornamental design for a plumbing fitting, as shown and described.

DESCRIPTION

FIG. 1 is a right, top, front perspective view of a plumbing fitting according to our new design;

FIG. 2 is a right side elevational view thereof, the left side elevational view thereof being a mirror image of the right side shown;

FIG. 3 is a front elevational view thereof;

FIG. 4 is a rear elevational view thereof;

FIG. 5 is a top plan view thereof;

FIG. 6 is a bottom plan view thereof;

FIG. 7 is a right, top, front perspective view of a plumbing fitting according to another embodiment of our new design;

FIG. 8 is a right side elevational view thereof, the left side elevational view thereof being a mirror image of the right side shown;

FIG. 9 is a front elevational view thereof;

FIG. 10 is a rear elevational view thereof;

FIG. 11 is a top plan view thereof; and,

FIG. 12 is a bottom plan view thereof.

The broken line representations in the figures are for the purpose of illustration only, and form no part of the claimed design.

In a preferred embodiment, the nature of this product is a plumbing fitting in the form of a faucet, having a spout and control handle, for washing various items.

1 Claim, 8 Drawing Sheets
